UNITED STATES PATENT OFFICE.

ROBERT LIDDELL, OF TECUMSEH, NEBRASKA.

HYDROCARBON-BURNER.

1,028,892.

Specification of Letters Patent. Patented June 11, 1912.

Application filed August 24, 1910. Serial No. 578,710.

To all whom it may concern:

Be it known that I, ROBERT LIDDELL, a citizen of the United States, residing at Tecumseh, in the county of Johnson and 5 State of Nebraska, have invented new and useful Improvements in Hydrocarbon-Burners, of which the following is a specification.

This invention relates to improvements 10 in hydrocarbon burners and particularly to a type of burner designed to be arranged in the fire-box of a range, and has for an object to provide a simple construction of a device of this character wherein the flame 15 when discharged from the burner will be spread considerably so as to be thoroughly distributed substantially throughout the heating area of the range.

In the drawing, forming a portion of 20 this specification and in which like numerals of reference indicate similar parts in the several views:—Figure 1 is a transverse section through a portion of the fire-box of the stove showing the application of the 25 burner thereto. Fig. 2 is a top plan view of the tray. Fig. 3 is a perspective view of the cover.

My improved hydrocarbon burner comprises a tray 1 which preferably embodies a 30 bottom 11, the downwardly and inwardly inclined wall 5, the vertical wall 6 and the downwardly and inwardly inclined walls 7 and 8. A longitudinally extending apron 12 is formed integral with the bottom 11, and 35 as illustrated, the lower portion 12' thereof extends downwardly at an angle toward the flared wall 5 of the tray. The upper edge of the apron is spaced from the top of the tray, and as shown, fitting thereover is 40 the inlet end of a liquid fuel supply pipe 15.

The tray is provided with a surrounding cleat 10 which is fitted in a correspondingly formed rabbeted portion in the bottom of the fire-box. A cover member 13 partly 45 closes the upper end of the tray, and as shown, it is provided with a depending apron 14 which extends in the direction of the flared wall 5 of the tray, the lower edge of the said apron being spaced from the

bottom 11, as shown. The cover-forming 50 member 13 is formed with a rib A by means of which the cover can be readily removed from the tray.

From the construction described it will be seen that the walls 5, 7 and 8 and the 55 apron 14 form collectively a discharge nozzle B which is provided with a contracted or relatively narrow inlet C and a flared or relatively large discharge D, the latter opening directly into the fire-box. The inclined 60 portion 12' of the apron is disposed immediately beneath the discharge end of the liquid fuel supply pipe and it extends in the direction of the wall 5 so that the oil 65 will be directed to the reduced inlet end C of the nozzle.

It will be understood that the fire-box is provided with the usual draft regulated openings (not shown) which provides for the required mixture of air with the oil to 70 insure the proper combustion of the fuel.

Owing to the peculiar construction of the nozzle which, as hereinbefore stated, is provided with a relatively large or flared upper 75 end and a relatively small or reduced lower end, the flame will be spread considerably immediately at its point of entrance into the fire-box.

I claim:

A liquid fuel burner comprising a tray 80 having an upwardly and outwardly inclined wall, an apron formed on the bottom of the tray and having a portion inclined in opposite direction of the said inclined wall, a liquid fuel discharge pipe having its discharge end disposed immediately above the 85 said inclined portion of the apron, and a cover partly closing the tray and formed with a depending member which extends at an angle toward the said inclined wall of 90 the tray, the said member having its lower end spaced from the bottom of the tray.

In testimony whereof I affix my signature in presence of two witnesses.

ROBERT LIDDELL.
